CLAIM

The ornamental design for a combined golf ball and tee positioner, as shown and described.

DESCRIPTION

FIG. 1 is a top perspective view of a combined golf ball and tee positioner, the broken line showing of a tee, golf ball and landscaping is for illustrative purposes only and forms no part of the claimed design.

FIG. 2 is a front elevational view thereof.

FIG. 3 is a rear elevational view thereof.

FIG. 4 is a right side elevational view of the combined golf ball and tee positioner.

FIG. 5 is a left side elevational view thereof.

FIG. 6 is a top plan view of the combined golf ball and tee positioner; and,

FIG. 7 is a bottom plan view thereof.
